Frank D. Kent

UNITED STATES PATENT OFFICE

LINNAEUS T. SAVAGE, OF EAST ORANGE, NEW JERSEY

DESIGN FOR A TOY CLIMBING TRACTOR

Application filed March 11, 1929. Serial No. 30,424. Term of patent 14 years.

To all whom it may concern:

Be it known that I, LINNAEUS T. SAVAGE, a citizen of the United States of America, and resident of East Orange, county of Essex, and State of New Jersey, have invented a new, original, and ornamental Design for a Toy Climbing Tractor, of which the following is a specification, reference being had to the accompanying drawing, forming part thereof.

The figure of the drawing is a front perspective view of a toy climbing tractor showing my new design.

I claim:

The ornamental design for a toy climbing tractor, as shown.

LINNAEUS T. SAVAGE.
